UNITED STATES PATENT OFFICE.

HOWARD SAMUEL SEMMEL, JOHN WILLIAM BALLIET, AND STEPHEN JOSHUA SCHAFER, OF SLATINGTON, PENNSYLVANIA.

SCHOOL-SLATE.

SPECIFICATION forming part of Letters Patent No. 451,336, dated April 28, 1891.

Application filed December 1, 1890. Serial No. 373,108. (No model.)

To all whom it may concern:

Be it known that we, HOWARD SAMUEL SEMMEL, JOHN WILLIAM BALLIET, and STEPHEN JOSHUA SCHAFER, all citizens of the United States, residing in the borough of Slatington, county of Lehigh, and State of Pennsylvania, have invented new and useful Improvements in School-Slates, of which the following is a specification.

10 This invention is an improvement in school-slates, and its object is to provide a cheap, noiseless, and durable frame for the slates; and it consists in the novel construction of the frame, as will be clearly understood from 15 the following description and claims, when taken in connection with the accompanying drawings, in which—

Figure 1 is a face view of the slate and frame. Figs. 2 and 3 are enlarged detail sectional views thereof.

20 A represents an ordinary slate.

B B are two continuous framing-strips of metal cut to partially frame the slate, placed on opposite sides and extending over the 25 edges thereof, as shown.

C designates the binding or buffer surrounding the edges of the slate and formed of any suitable material, as felt, and nearly a complete circle in cross-section, but having 30 lateral inwardly-extending lips c c, which embrace the edges of the slate. The buffer may be made tubular and inclose a heavy filling cord F and a filling-strip D, which is inserted between the edges of the slate and 35 cord F. The cord and strip may be of paper or any suitable material and might be formed integral. The binding C is drawn tightly over the cord and strip, and the lips c extend over the edges of the slate even with the in-

40 side edges of the strip B, which cover the said lips and inclosed strip D and slate edges, as shown, thereby protecting the slate, as indicated at x x, Fig. 3. The strips B are preferably slightly beveled on their edges, as 45 shown. After applying the binding C with

cord F and strip D and the frame-strips B they are pressed into proper frame shape and the parts secured together by rivets E, as indicated in the drawings. Of course any suitable fastenings may be used to unite the 50 parts, such as eyelets or staples in place of rivets. We prefer to use a heavy cord or roll F of paper or other suitable material covered with cloth or felt binding, as C, substantially as shown; but evidently in some instances 55 the binding C and cord F or binding-cord and strip D might be made integral of the same material, such as rubber, paper, &c., if desired, and secured to the edges of the slate, as described. We prefer to make the frame- 60 strips B of metal; but they can be made of any suitable stiff material, as wood.

What we therefore claim as new is—

1. The combination of the slate and the binding or buffer surrounding and having 65 laterally-projecting lips inclosing the edges of the slate, with the independent frame-strips on opposite sides of the slate applied over said lips and united together through the lips at the edges of the slate, so as to bind the 70 buffer thereto, substantially as described.

2. The combination of the independent frame-strips B, the binding or buffer C, having a roll F, strip D, and lips c, constructed and arranged substantially as specified. 75

3. In a slate-frame, the combination of a strip surrounding the edge of the slate, a roll extending around said strip, a binding inclosing both roll and strip and extending inwardly over the edges of the slate, with two 80 independent frame-strips inclosing parts of the binding-strip and edges of slate and united to fasten all parts of the frame together, substantially as described.

HOWARD SAMUEL SEMMEL.

JOHN WILLIAM BALLIET.

STEPHEN JOSHUA SCHAFER.
